UNITED STATES PATENT OFFICE

THOMAS S. LEWIS, OF MEMPHIS, TENNESSEE

ACROBATIC TOY

Application filed May 22, 1931. Serial No. 539,185.

This invention relates to acrobatic toys in which a figure in the shape, preferably of a monkey is caused to reproduce in a mechanical way, an indefinite number of gymnastic stunts similar to those which are performed by acrobats or gymnasts with the aid of rotatable trapeze apparatus.

The objects of the invention are:

To provide a trapeze apparatus of novel form and a complementary acrobatic figure adapted to coact therewith when the trapeze apparatus is rotated and thereby to accomplish a variety of stunts.

The means by which the foregoing and other objects are accomplished and the manner of their accomplishment will readily be understood from the following specification on reference to the accompanying drawings, in which:

Fig. 1 is a side elevation of the preferred form of my device showing portions thereof broken away to more clearly illustrate the construction.

Fig. 2 is a fragmentary plan view of one of the swinging arms and the auxiliary trapeze carried thereby.

Fig. 3 is a fragmentary transverse elevation showing a portion of the other of the auxiliary trapezes and the associated carrying arm.

Fig. 4 is a side elevation of a modified form of the device showing a motor drive in connection therewith.

Fig. 5 is a plan view of the trapeze portion of this form of the device; and

Fig. 6 is an enlarged transverse elevation of the acrobatic figure used.

Referring now to the drawings the device comprises essentially a base 10, having a pair of frame members 11 extending vertically upward therefrom and spaced apart. Journalled in the top of this frame is a transverse shaft or rung 12 which has a handle member 13 integral therewith. The main trapeze unit comprises this central rung, a pair of hub members 14 mounted on and secured thereto and arms 15, 15-A; 16, 16-A; 17, 17-A and 18, 18-A, secured in and radiating from this hub.

The arms 15 and 17 are at right angles to

the arms 16 and 18 and the arms 15, 15-A, etc., are transversely spaced apart. Disposed between and connecting the arms 15, 15-A are rungs 19 and 20 and between the arms 17, 17-A a similar set of rungs, the rung 19 being equally spaced from the center 12 and the outer rung 20. Between the arms 16, and 16-A there is a single rung 21 only which rung is spaced the same distance from the center rung as is the rung 20, and the same condition is true with regard to the arms 18 and 18-A. For purposes of definition in the claims, the rung 21 has been designated as a pivot rung. Pivotedly mounted on the pivot rung 21 is an auxiliary trapeze which comprises a pair of spaced bars 22, 22-A between which extend rungs 23, 24 which are the same distance from the pivot rung 21 as is the rung 19 from the center rung 12. The auxiliary trapeze turns freely about the pivot rung 21 except that it is provided with a projecting lug or stop 25 on one end, which engages against the bars preventing further motion and which when rotated clockwise in Fig. 1, will align the bars 22 and 16 and position the rung 23 half way between the rung 21 and the center rung 12, this position being at such time the same relatively to the bars 16, 16-A as the rung is to the bars 15, 15-A. 26 is a counterweight which balances the weight of the stop 25 on the opposite end of the trapeze, but which may be slightly heavier in order that the stop 25 may be held against the bar 16 during rotation of the device.

In Figs. 4 and 5 a modification of the device is shown in which all the arms 27, 27-A are identical and are provided with identically positioned rungs 28 and 29. The center rung 12 in this form is identical with the center rung of the first mentioned form of the device and an identical handle 13 is used if desired. In this form of the device the arms and rungs conform to the arms 15, 15-A and the rungs 19, 20 of Fig. 1, the auxiliary trapeze members being omitted. This form of the device may be provided with a frame similar to the frame 11 or with a frame 30 shown, which frame likewise is equally applicable to Fig. 1. The device may be provided with a motor 31, 100

pulley 32 secured to the trapeze unit and a driving belt 33.

The trapeze performer is preferably in the form of a monkey having a body 34 a head 35, a pair of arms 36 oscillatably hinged or pivoted as on pins 37, swinging legs 38 and a rigid tail 39. Each of the arms is provided with two hooks 40, 41, which are oppositely faced and which engage the rungs of the ladder from opposite directions. Preferably the arms are braced apart by a cross rod 42 which holds them parallel and cause them to swing concurrently. The arms 36 if swung upward counterclockwise in Fig. 4, are stopped in alignment with the body by a pin 43 against which they strike. Clockwise in this view they may swing around until they strike the legs 38, but are thereby restrained from further movement. The spread of the arms serves to balance the figure in its swing. The tail 39 extends definitely below the ends of the legs 38 so that they will not interfere with its action and preferably it extends backward out of alignment with the body of the figure. The tail is provided with a hook 44 the end 45 of which hook curls slightly inward. The length of the figure is such that with the hooks 40 engaging a rung, the tail 39 would strike against a rung passing therebelow just clear of the hook 44, and so that such hook would be entirely free therefrom, and thereafter when the figure is carried around by movement of the trapeze, longitudinal shifting would engage such hook with the rung and disengage the other hook.

In using the toy one or more of the figures is hung by arms or tail from the rungs of the trapeze. Where two are used at the same time they are of course spaced transversely apart on the rungs so that they will clear each other. The handle is turned clockwise and the figures swing downward from the rungs as shown in Fig. 1. When the rung on which they are suspended passes its top center the hook on the opposite end of the figure swings against an additional rung and as movement continues transfer is made to such rung. It is found that in turning the device the figures will shift from auxiliary trapeze to main trapeze and back and execute numerous unexpected transfers from rung to rung. Reversal of the direction of rotation causes an additional shift, and complexity of action.

It will be understood that modification of the detail of construction of both the trapeze and figure may be made without departing from the spirit or intent of my invention, and that I do not restrict myself to such detail except as it may be specifically set out in any particular claim.

Having described my invention, what I claim is:

1. In an acrobatic toy, a frame and a rotatable trapeze unit supported by said frame; said unit comprising a central rung rotatably

mounted in said frame, means for rotating said rung, opposed side members, each consisting of a pair of arms crossing at right angles and secured to said rung, one of said arms and its opposite arm being additionally connected by four transverse rungs spaced two on each side of said central rung at equal intervals therefrom, the remaining arms being connected by a pair of pivot rungs oppositely spaced at twice such interval from the central rung, and auxiliary trapezes rotatably mounted one on each of said pivot rungs, said auxiliary trapezes each comprising a pair of centrally pivoted bars connected by a pair of rungs oppositely spaced at the first mentioned interval from said pivot rung, means on each of said trapeze members engaging said arms to prevent complete rotation of said trapeze bars, and align them with said arms, and a figure having hooks at both ends, engageable with a rung, and tumbling from rung to rung as said unit is rotated.

2. In an acrobatic toy, a frame, a rotatable trapeze unit supported by said frame, said unit comprising a central rung rotatably mounted in said frame, means for rotating said rung, opposed side members, each consisting of a pair of arms crossing at right angles and secured to said rung, one of said arms and its opposite arm being additionally connected by transverse rungs spaced on each side of said central rung at equal intervals therefrom, the remaining arms being connected by a pair of pivot rungs oppositely spaced at twice such interval from the central rung, and trapeze members one turnably mounted on each of said pivot rungs, said trapeze members each comprising a pair of centrally pivoted bars connected by a pair of rungs oppositely spaced at the first mentioned interval from said pivot rung, means on each of said trapeze members engaging said arms to prevent complete rotation of said trapeze bars, and align them with said arms, and a figure having hooks at both ends, engageable with a rung, and tumbling from rung to rung as said unit is rotated.

3. In an acrobatic toy, a rotatable trapeze unit having rungs, and a trapeze performer cooperating therewith, said performer comprising a body, legs, oscillatable arms projecting beyond said body, and a tail projecting downward beyond said legs, means for limiting the swing of said arms from a downward and rearward position upwardly and forwardly to a position in substantial alignment with said body, said arms each having a pair of oppositely faced hooks at its outer end whereby engagement with said rungs may be accomplished in either direction of trapeze rotation, and said tail having a hook on the end thereof facing rearwardly.

4. In an acrobatic toy, a rotatable trapeze unit having rungs, and a trapeze performer

cooperating therewith, said performer comprising a body, oscillatable arms projecting beyond said body, means compelling concurrent movement of said arms, and a tail projecting downward below said body, means for limiting the swing of said arms from a downward and rearward position upwardly and forwardly to a position in substantial alignment with said body, said arms each having a forwardly faced hook at its outer end, and said tail having a hook on the end thereof facing rearwardly.

5. In an acrobatic toy, a rotatable trapeze unit having rungs, and a trapeze performer cooperating therewith, said performer comprising a body, oscillatable arms projecting beyond said body, means compelling concurrent movement of said arms, and a tail projecting downward below said body, said arms each having a pair of oppositely faced hooks 10 at its outer end whereby engagement with said rungs may be accomplished in either direction of trapeze rotation, and said tail having a hook on the end thereof facing in a single direction.

25 In testimony whereof I hereunto affix my signature.

THOMAS S. LEWIS.
